UNITED STATES PATENT OFFICE.

HENRY BODDIKER, OF CHICAGO, ILLINOIS, ASSIGNOR TO MERGENTHALER LINOTYPE COMPANY, A CORPORATION OF NEW YORK.

TYPOGRAPHICAL MACHINE.

1,315,277.

Specification of Letters Patent. Patented Sept. 9, 1919.

Application filed November 27, 1917. Serial No. 204,144.

To all whom it may concern:

Be it known that I, HENRY BODDIKER, a citizen of the United States, residing at Chicago, in the county of Cook and State 5 of Illinois, have invented certain new and useful Improvements in Typographical Machines, of which the following is a specification, reference being had therein to the accompanying drawing.

10 My invention has reference to linotype machines of the general organization represented in Letters Patent of the United States, No. 436,532 to O. Mergenthaler, wherein circulating matrices are released from a channeled magazine in the order in which their characters are to appear in print, and then assembled in line, together with expanding spacers, the composed line transferred to the face of a mold, the mold filled 15 with molten metal to form a slug or linotype against the matrices which produce the type characters thereon, and the matrices thereafter elevated and returned through a distributing mechanism to the magazine from 20 which they started. More particularly the invention relates to the escapements and their operating devices, which are employed in such machines to control the discharge of the matrices from the magazine channels. 25 These escapements are commonly operated by power actuated devices initiated in their operation by the manipulation of the key levers of the keyboard, the motion of the power devices being transmitted to the escapements through the medium of actuating 30 reeds.

It may sometimes happen, in the operation of the machine, that the movement of an escapement will be resisted by a matrix 40 lodging in improper position in the magazine, or by other abnormal conditions, and in such event, it is desirable that the parts may yield so as to prevent their breakage or undue strain thereon. To meet this condition various expedients have been resorted to, characterized by the yielding mounting of some one of the elements in the connections between the key lever and the escapements, springs of different forms 45 and differently applied being employed to hold the parts so that they will normally perform their functions and yet allow them to yield in the event of undue resistance. Certain objections have been developed in 50 the use of these expedients, mainly on ac-

count of the inaccessibility of the springs and the more or less complicated arrangement of the parts. My invention aims to simplify the construction and to so arrange the parts that the springs will be readily 60 accessible for inspection, repairs or replacement.

The invention is shown embodied in a form of escapement actuating mechanism in which the escapements are operated by 65 a series of actuating levers which overlie the upper ends of the reeds, which levers are pivotally mounted at their lower ends and are rocked about the pivots by the reciprocation of the reeds and act at their 70 upper ends on the escapement mechanisms, and the invention consists in sustaining the pivotal end of the lever so that in the event of resistance being offered to the movement of its free end, it will yield at its point of 75 pivotal support, and in combining with the lever thus sustained, a spring bearing thereon, and normally holding it against yielding movement, but adapted, under abnormal conditions and when resistance is offered, 80 to yield and permit the lever to shift on its pivot and thereby prevent strain or injury to the operating parts, the said springs for the several levers being so disposed that they 85 will be ready of access for repairs, replacement, etc.

In the accompanying drawings:

Figure 1 is a vertical sectional elevation through the lower discharge end of the magazine, showing one of the escapements, 90 the actuating lever therefor, and the operating connections to the keyboard.

Fig. 2 is a similar view with certain parts omitted and showing how the actuating lever yields when resistance is offered to its 95 normal operation by the lodgment of a matrix in improper position.

Fig. 3 is a rear sectional elevation on the line 3—3 of Fig. 1, showing a number of the yielding actuating levers and the springs 100 acting thereon.

Referring to the drawing:

1 designates the lower discharge end of a magazine of a linotype machine containing channels 2 (one only being shown), in which matrices 3 are stored and from which they are discharged by escapements 4 into an assembler entrance 5, for composition in the line, it being understood that there are a number of magazine channels arranged 105 110

side by side to accommodate matrices bearing different characters, and one escapement for each channel, all as usual in linotype machines of the Mergenthaler type.

5 The escapement in the present instance consists of a pivoted escapement lever 6 carrying two pawls or dogs which are projected alternately into the magazine, and which, coöperating with the ears on the matrices, control the passing matrices and effect their delivery in succession from the magazine channel. Each escapement lever is acted on by a spring 7 attached to the frame of the machine and tending to reverse the position of the lever and project 10 one of the pawls into the magazine. Each escapement lever is also acted on directly by a plunger 8 guided in the machine frame, with its outer end exposed, and these several plungers are acted on by actuating levers 15 9 which are arranged side by side and extend rearwardly and downwardly in an inclined position beneath the magazine and above a series of vertical actuating reeds 10 (one only being shown) by which the levers are operated. The levers 9 are pivotally sustained at their lower ends and are engaged on their under sides by the upper ends of the reeds, the lower ends of which 20 are disposed over the usual cam yokes 11, each of which carries a rotary operating cam 11^a which is adapted, when the yoke is tripped by the actuation of a key lever 13 of the keyboard, to engage a constantly operating power driven roller 14, and be rotated thereby and thereby reciprocate the 25 reed vertically.

The foregoing parts may be of the usual and ordinary construction and they constitute a key-controlled power operated mechanism for the escapements, characteristic of the Mergenthaler machine, and in themselves form no part of the present invention.

30 In applying my invention I so mount the lower ends of the escapement actuating levers 9, that while they will be pivotally supported to adapt them to be swung back and forth at their upper ends by the reeds 35 and thus operate the escapements, they will at the same time be capable of yielding bodily at their lower pivotal ends in the event of obstruction or resistance being offered to their normal movement, as for 40 instance by the lodgment of a matrix in a position obstructing the action of the escapements; whereby injury or strain on the parts will be prevented.

45 This I accomplish by forming each lever 60 in its lower end with an open slot or recess 15, which slots of the several levers are engaged over a horizontal pivot rod 16 fixed between upstanding ears 17 on the machine frame, the form and disposition of the slots 55 being such that the lever may shift slightly

on the pivotal rod upwardly and rearwardly. Each lever 9 is acted on by a spring finger 18, which springs are sustained at their lower ends by the machine frame and extend upwardly and forwardly and have 60 their upper free ends bearing with yielding pressure on the upper edges of the actuating levers at points substantially directly over the pivot rod and in line with the slots therein. These spring fingers in 65 the present instance consist each of a section of spring wire formed near its lower end with a spring coil 18^a, terminating in a portion 18^b which is seated loosely in corresponding holes or openings in a horizontal 70 sustaining bar 18^c on the machine frame. The coiled springs are held in place upon the sustaining bar by means of an angle plate 20, the horizontal portion of which is secured to the bar by screws 20^a and the vertical portion of which extends upwardly behind the coils 18^a and thus confines the portions 18^b to their seats. The sustaining bar 18^c is itself detachably connected to the 75 machine frame by means of screws or other fastening devices 19. As a result of this arrangement, the springs may be applied to or removed from the machine frame as a unit, this being permitted by the free engagement of the portions 18 with the escapement levers 9, which engagement is made and broken as the frame is applied and removed 80 respectively. In addition, by removing the plate 20 any selected one of the spring sections may be readily removed independently 85 of the others and replaced by another, and this whether the sustaining bar be connected to or disconnected from the machine frame. Furthermore, the flexible nature of 90 the springs permits the ready and independent removal and replacement of any one of the escapement levers 9, it merely being necessary to displace the portion 18 of the corresponding spring laterally to disengage 95 it from the escapement lever. 100

The springs thus act to hold the slotted ends of the actuating levers down on the rod, so that these ends will pivot thereon as the levers are swung up and down by the reeds in the normal operation of the escapements, as shown in Fig. 1, while at the same time the springs will allow the slotted ends of the levers to yield or shift outwardly 105 from the pivot rod relative to the normal axis under abnormal conditions as shown in 110 Fig. 2.

115 In the operation of the mechanism the vertical reeds, reciprocated by the power actuated devices brought into operation by the manipulation of the key levers, will swing 120 the actuating levers on their pivotal axes and their upper ends engaging the escapement plungers 8, will thus operate the escapements, the lower slotted ends of the actuating levers being held down yieldingly on 125 130

the pivot rod by the spring fingers as shown in Fig. 1. In the event, however, of resistance or obstruction being offered to the movement of the lever, such as would be caused for instance by the lodgment of a matrix in an improper position with its shoulder in the path of movement of the escapement pawl, the vertical movement of the reed will force the lower slotted end of the lever off the pivotal rod against the resistance of its spring finger 18, as shown in Fig. 2, and thus permit the actuating lever to yield, the lever in this yielding movement fulcruming at its upper end on the restrained escapement plunger. In this way the power device may complete its operating action on the reed without causing any strain on the parts or injury to or breakage of the same.

It will be noted that by reason of the fact that the spring fingers bear on the actuating levers at or adjacent their points of pivotal support on the pivot rod, and substantially in line with the open slots in the levers, the springs will offer little or no resistance to the normal operation of the levers in their pivotal motion, the function of the springs being to exert sufficient pressure on the levers to hold them down on the pivot rod without offering any substantial resistance to the normal movements of the levers, while at the same time they will permit the levers to yield or shift at their pivotal ends under abnormal conditions, as when undue strain is offered to their movement.

Furthermore it will be observed that by the arrangement of the springs in the particular manner shown, they are exposed and will therefore be easy of access for inspection, repairs or replacement. In the event of breakage or injury to them, they may be readily removed independently of each other, and replaced or repairs made, inasmuch as they are not arranged behind or between parts difficult of access.

The particular form of the springs produces a simple and inexpensive construction, which operates with effectiveness, and by reason of the disposition and arrangement of the springs the parts may be readily assembled and disassembled.

In the foregoing description and accompanying drawing I have set forth my invention in the particular form and detailed construction which I prefer to adopt, but it will be understood that the details may be modified and changed without departing from the limits of my invention, provided

the operation is substantially as indicated above, and further it will be understood that the invention is not limited to any particular form or construction of the parts except in so far as such limitations are set forth in the claims.

Having thus described my invention, its construction and mode of operation, what I claim and desire to secure by Letters Patent of the United States, is as follows:

1. In a typographical machine, the combination with an escapement operating mechanism including a series of pivoted members formed with open slots to engage the pivot so as to yield in the event of undue resistance to their movement, of a corresponding series of springs having free ends arranged in engagement with or bearing upon the pivoted members adjacent their pivot to hold them normally in operative relation thereto, and a supporting bar wherein the opposite ends of the springs are seated, said supporting bar being detachably connected to the machine frame so as to enable the springs as a unit to be applied to or removed from the machine, and the springs being arranged in said supporting bar so as to be engaged with and disengaged from the pivoted members as the supporting bar is applied to and removed from the machine.

2. A combination as specified in claim 1, characterized by the fact that the springs are detachably connected to the sustaining bar so as to be insertible therein or removable therefrom individually and independently of each other.

3. A combination as specified in claim 1, characterized by the fact that the sustaining bar is formed with a series of openings wherein the confined ends of the springs are loosely engaged and further is provided with a retaining plate which is detachably secured thereto so as to be removable to permit the insertion or removal of the springs.

4. A combination as specified in claim 1, characterized by the fact that the springs therein recited are in the form of coiled wire sections.

5. A combination as specified in claim 1, characterized by the fact that the springs therein recited are yieldable laterally to permit their free ends to be disengaged from the pivoted members mentioned so as to permit their ready removal and replacement.

In testimony whereof I have affixed my signature hereto.

HENRY BODDIKER.
